UNITED STATES PATENT OFFICE.

CHARLES LA DOW, OF ALBANY, NEW YORK.

PULVERIZER.

SPECIFICATION forming part of Letters Patent No. 404,291, dated May 28, 1889.

Application filed January 6, 1887. Serial No. 223,616. (No model.)

To all whom it may concern:

Be it known that I, CHARLES LA DOW, of the city of Albany, county of Albany, State of New York, have invented a new and useful Improvement in Pulverizers, of which the following is a specification.

My invention relates to pulverizers having opposing gangs of cutters revolving across the line of draft.

- 10 In the drawings, Figure 1 represents a top view of my invention, in which the gangs are composed of solid sheets of metal twisted spirally; also, showing by dotted lines that the draft devices may be reversed on the journal-bearings of the gangs. Fig. 2 represents a rear view of Fig. 1, showing by dotted lines the vertical vibration of the inner ends of the gangs when coupled as shown in Figs. 1 and 2, and also represents my method of providing room for the buffers between the inner ends of the gangs, while bringing the cutting-edges of the inner ends of the gangs into such proximity as will practically leave no earth unworked between the gangs. Fig. 3 represents an end view of my invention, showing by dotted lines that the seat-bar is hinged to and may vibrate up and down on the draft-pole; also showing by full and dotted lines the positions to which the pendent seat-support may be adjusted relatively to the center draw-bar, C; also showing by dotted lines the vertical vibration of the cutters and the position of the draw-bar C when reversed. Figs. 4 and 5 represent a top and rear view of my invention, in which spiral strip-cutters are mounted upon each other, so as to form two opposing gangs of right and left hand screw-cutters, adapted to abut directly against each other to counteract their end-thrust, substantially in line with that part of the gang where the end-thrust is created, (through the dotted lines indicated by the arrows in Fig. 5,) the end-thrust being received on the wheel *r* at the points *F F* in said Fig. 5. Fig. 6 is an end view of the outer end of one gang. In these figures the gangs are capable of dropping below a straight line at their inner ends, as shown in dotted lines in Figs. 5 and 6. Fig. 7 represents a detail top view of the inner ends of the gangs, the arrow in full line indicating the direction in which the gangs

are drawn when it is designed that the opposing cutters shall cut up and pulverize the soil, and the arrow in dotted line indicating the reverse direction in which the machine 55 is drawn when it is desired to draw the gangs of cutters over the ground without cutting it up. Fig. 8 represents by full lines sections of those portions of the blades (of both right and left hand gangs) which rest on the ground 60 and do the work of cutting up the soil, in which figure it will be seen that the blades are set dishing, (or at an angle vertically,) with those in one gang set with an opposite dish or pitch to those in the other gang. Figs. 65 9 and 10 are sections of the gang twisted out of sheet metal, but in such form as shall give the cutting-blades substantially the same vertical dish or pitch as given to the spiral strip-blades, as shown in Fig. 8. The 70 gangs, when made of sheet metal and twisted, as shown in Figs. 9 and 10, are made right and left hand, so as to counteract the side-thrust of each other. Fig. 11 shows a sectional view of the inner ends of the gangs 75 and their buffer-rings; also the forked rear end of the draw-bar C and the wheel *r* for receiving the end-thrust of the buffer-rings at the lower sides of the rings and as near in the direct line of the side-thrust as can be 80 without carrying the buffer-rings so low as to retard the cutters of the inner ends of the gangs from entering the soil sufficiently. This view also shows that the web (which is attached to the buffer-rings) is concaved in- 85 ward from its fellow, in order to admit of the rear end of the draw-bar C and its wheel-supporting devices being maintained between the inner ends of the gangs without spreading the opposing cutters of the gangs 90 farther apart than shall give them room in which to revolve without interfering with the draw-bar C, as it is very important that the cutters of one gang shall revolve in close proximity to the cutters of its fellow gang. 95 Fig. 12 represents a view of the inner end of one gang, a side view of the draw-bar C and the angle thereon, carrying a wheel for receiving the side-thrusts of the lower side of the buffer-rings *h* of each gang, which abut 100 against said wheel on opposite sides thereof, respectively.

In the drawings, in Figs. 1, 2, and 3 A is the pole; B B', the gangs of sheet-metal cutters; C, the draw-bar connecting the inner ends of the gangs to the pole in such manner that said inner ends may have vertical vibration; D D', the hounds; G, the center box for coupling the buffers *o o* together; R, the socket for hinging the seat-bar to the pole, and R' the seat-socket for holding the seat-bar when the pole is turned upside down for reversing the action of the cutters and drawing the gangs in the opposite direction; *d d*, the pendent hanger for transmitting the driver's weight directly to the inner ends of the gangs; *n n*, notches in the draw-bar C for preventing the pendent hanger from slipping lengthwise of the draw-bar and to regulate the amount of weight imparted by the driver. *m m'* are hammer-straps on opposite sides of the pole. *t t* are the outer journal-bearings.

In the drawings shown in Figs. 4, 5, 6, 7, 9, 10, 11, and 12 the gangs are represented by letters B B'; C, the draw-bar, which terminates in a draft-hook, *m*. *h h* are buffer-rings having contact at F F with the wheel *r* for counteracting the end-thrusts of the gangs abutting directly against each other at their inner ends through their medium *r*. *w* is a web attached to each buffer-ring, the projections of the web beyond the circumference of the buffer-rings being riveted to the spiral strip-cutters in the manner shown in Figs. 4, 5, 6, 7, 11, and 12.

The buffer-rings may be attached to the sheet-metal gangs, as shown in Figs 1 and 2, in the same manner as attached to gangs made from spiral strips of metal.

It will be observed that the web *w* is concaved in one gang in a direction opposite to the concave in its fellow gang, the draw-bar C, its hubs *u u*, the bifurcated elbow or angle, and the wheel *r*, operating between said concaved web. The end-thrust of the gangs causes the lower side of the buffer-rings to abut closely against the wheel *r* at F F and revolve said wheel, so that it is in effect an anti-friction wheel. The thickness of the wheel fills the space between the adjacent bottom sides of the buffer-ring, so that the center of the gangs will not rise unduly, as the wheel *r* acts as a fulcrum against the pin *o* and prevents such movement, thus adapting the inner ends of the gangs to level a ridge and divide the earth and turn the same in opposite directions. The gangs can drop at their inner ends, as shown by dotted lines *y y* in Fig. 5, in which position they will cut into the bottom of the furrow or other depression; but in all cases the gangs cut so close at their inner ends that no furrow or ridge is left unworked between them.

By referring to the drawings, in Fig. 1 it will be seen that the gangs B B' are formed of sheet metal, and are also recessed at their inner ends for the reception of the buffers, which in said figures are attached directly to the journal-pins on which the gangs revolve,

so that the result of bringing the inner ends of the cutter-gangs of sheet metal close together and yet leave room for buffer mechanism between said gangs is the same as when the gangs are composed of spiral strip-cutters. When the gangs abut in line with their axles, as shown in Figs. 1, 2, and 3, they are free to vibrate both up and down at their inner ends, and as the side-thrusts of the soil against the screw-faces of the cutters tend to lift the inner ends of the gangs and to cause them to cut deepest at their outer ends I overcome said defect by a hanger (pendent from the seat-bar) which rests upon the draw-bar C, and thereby prevents the draw-bar from rising above the height desired. The vertical movement of the rear end of said draw-bar may be regulated by varying the position of the pendent hanger either angularly, as shown in dotted lines, or by varying its position by the holes in the upper end thereof. Its lower end may be engaged with any of the notches in the draw-bar, or said bar may be left without notches. It will be observed by reference to dotted lines in Fig. 3 that the seat-bar is hinged to and may vibrate vertically in its socket on the pole, in order to permit the inner ends of the gangs to rise considerably should a stone or ridge be encountered. When the buffer-rings are used, this pendent hanger may be omitted, as said rings having contact at their bottom ends effectually prevent the inner ends of the gangs from rising unduly. The seat-bar is hinged to its socket in a way that permits the seat to be readily removed when the pole is to be turned over and inserted into a similar socket which is attached to the opposite side of the pole. The seat is unhinged and withdrawn from the socket R, the pole and frame thrown over, as shown in dotted lines in Figs. 1 and 3, and the seat inserted into socket R', for the purpose which I will now describe.

So far as known to me, in harrows having two opposing independently-revolving gangs of cutters it has always been customary and necessary to set the opposing gangs at oblique angles to the draft and to each other, in order to cause them to enter the ground sufficiently to cut up and pulverize the same; but in my invention, as exhibited in all the figures, I place the opposing and independently-revolving gangs of cutters in line with each other, and at a right angle to the draft, and so form the cutters that they have within themselves the proper angle to turn furrows when they are drawn forward in a certain direction, the opposing right and left hand spirals causing the cutters to enter the ground, and the vertical pitch or dish of the spirals further aiding this result.

By reference to Fig. 7 it will be seen that the arrows in full lines indicate the direction in which these spiral gangs should be drawn to cause them to enter the earth, as the spiral blades of one gang, when drawn forward in that direction, form one half of the sharpened

ends of a series of wedges, and the opposing spirals in the other gang in effect form other halves of the said sharpened ends of the wedges, causing each gang to have great suction when drawn forward, as shown, so as to enter the ground deep and stir and turn it thoroughly.

No provision is made in this invention for setting the cutters at angles to each other, 10 and instead of such usual method, heretofore employed in revolving harrows to make the cutters enter the ground or roll over it without cutting it up, I shape the spiral cutters in my invention in such form that when the 15 draft is applied from the position shown by the arrow in dotted lines in Fig. 7 those portions of the gangs in contact with the ground will then present the blunt ends of a series of wedges, and the vertical pitch of the cutters, 20 which before presented to the draft a form which created suction when brought into contact with the soil, now presents to the draft a series of revolving runners having convex surfaces which ride on top of the earth without cutting it up. This result I obtain by reversing the draft-pole or draft-frame, preferably by throwing it over, as shown; but the draft devices may be reversed in other ways. When the draft-frame is provided with a seat, 25 it is desirable that the seat should be on top of said frame, and therefore I provide a way for reversing the seat when the frame is turned upside down. If the frame be turned around laterally, and its direction thus reversed, of course the seat may be turned with it. When 30 the seat is reversed, as shown in Fig. 3, the pendent hanger may be folded close to the seat-bar. The draft-pole is arranged for receiving the whiffletrees on opposite sides of the pole, and the neck-yoke tip is equipped 35 with a holdback on opposite sides of the pole.

The buffers, as shown in Figs. 1 and 2, may be omitted, and the buffer-rings and wheel, as shown in Figs. 4, 5, 6, 7, 11, and 12, may be 40 used with the gangs, as shown in Figs. 1, 2, and 3.

The form of draft-frame as shown in Figs. 4, 5, and 6 may be used with solid spiral gangs, as shown in Figs. 1 and 2; but in every 45 case I prefer to set the cutting portions of the blade at a vertical pitch or dish, as shown in Figs. 8 and 10.

The buffer-rings *h* have each a web, *w*, attached to them, and said webs are each concaved, as heretofore described, and they project beyond the rings to afford a means for attaching the rings to the blades by rivets, as shown. The center of each web is connected to the draw-bar *C* by a bolt, *o*. The 50 rear end of the draw-bar has an angle, preferably bifurcated and bent downward for the reception of a wheel, *r*, which should be a trifle thicker in cross-section than the draw-bar *C*. The buffer-rings at their lower sides 55 abut against this wheel and revolve it between them. This wheel *r* receives the end-thrust of each gang substantially in line with

the portions of the cutters which receive the end-thrust direct from the soil, preventing wear of the revolving parts and enabling the 70 gangs of this machine to remain flexible, so as to vibrate at their inner ends without being unduly raised by the end-thrust caused by the contact with the soil. The recess may be omitted and the wheel be made of any 75 size desired.

It is unnecessary to set these gangs at angles with each other; but such may be done if desired, and then the wheel *r* will have contact with the front sides of the buffer-rings. 80 I prefer to set the gangs in line with each other and form the proper angle in the cutters themselves, and thus avoid leaving such space unworked between the gangs as must necessarily be left in all machines where revolving gangs of cutters are set at angles to each other.

In other applications filed by me (Serial No. 221,401, filed December 13, 1886; Serial No. 223,202, filed January 3, 1887, and Serial No. 240,672, filed June 8, 1887) I have shown machines somewhat analogous to that herein illustrated, and I hereby disclaim in this case any subject-matter claimed in said applications.

Having described my invention, I claim—

1. In a pulverizer, a draft-frame, in combination with two independently-revolving opposing spiral cutters set in substantially a straight line with each other and adapted to turn furrows from each other as the implement is drawn forward.

2. In a pulverizer, a draft-frame, in combination with two independently-revolving and opposing spiral cutters adapted to cut and turn furrows in the soil when said cutters are set in line with each other.

3. In a pulverizer, a draft-frame, in combination with two spiral cutters, *B* *B'*, adapted to revolve independently of each other, said cutter-blades being adapted to enter the earth in substantially the position shown in Figs. 8 and 10 of the drawings.

4. In a pulverizer, a draft-frame, in combination with two independently-revolving and opposing spiral cutters, the blades of each cutter being supported by their ends only and shaped to have both horizontal angle and vertical pitch within themselves.

5. In a pulverizer, two spiral cutters adapted to oppose each other, in combination with a reversible draft-frame.

6. In a pulverizer, two cutters adapted to oppose each other, in combination with the frame *D* *D'* and bar *C*, said frame being adapted to be reversed on its journal-bearings.

7. In a pulverizer, a draft-frame, in combination with two opposing spiral cutters adapted to vibrate vertically at their inner ends.

8. In a pulverizer, a draft-frame, in combination with two independently-revolving spiral cutters adapted to turn furrows when set in line with each other, and adapted to

abut directly against each other at their inner ends.

9. In a pulverizer, a draft-frame, in combination with two independently-revolving spiral cutters recessed at their inner ends, substantially as shown.

10. In a pulverizer, a draft-frame, in combination with two independently-revolving spiral cutters adapted to turn furrows when drawn forward in one direction, and to roll over the ground without cutting it up when drawn backward, or in the opposite direction.

11. In a pulverizer, a draft-frame, in combination with two shaftless or hollow spiral cutters arranged on opposite sides of a central draft-line, the blades of one cutter opposing the blades of the other, so as to cut and divide the soil and turn it outward from between the cutters when the machine is drawn in one direction, and adapted to roll over the soil without cutting it up when the machine is drawn backward in the opposite direction.

12. In a pulverizer, a draft-frame, in combination with two revolving shaftless or hollow spiral cutters, the blades of one cutter being adapted to present an opposing angular and vertical pitch relatively to the other cutter, so as to create suction when revolved forward against the soil, and adapted to present a convex surface to the soil when revolved backward in the opposite direction.

13. In a pulverizer, a draft-frame and two gangs of cutters connected therewith, with the inner cutting-edges of the gangs in close proximity to each other, the inner ends of said gangs being formed with recesses extending into the gangs beyond their cutting-edges, in combination with mechanism located within said recesses and adapted to couple the inner ends of the gangs together.

14. In a pulverizer, the bar D D', or equivalent thereof, two cutters, and the bar C, or equivalent center connection, in combination with an angular or downward projection attached to the center connection and adapted to limit the vertical movement of the inner ends of the cutters.

15. In a pulverizer, the bars D D', or equivalent thereof, two cutters, and the bar C, or equivalent center connection, in combination with an angle or downward projection attached to the center connection, with the wheel *r* mounted on said projection.

16. In a pulverizer, a draft-frame, in combination with shaftless or hollow spiral cutters mounted upon each other in such manner as to have horizontal angles and vertical pitch within themselves.

17. In a pulverizer, a draft-frame and two spiral cutters, in combination with the buffer-rings *h h*, or equivalent mechanism, adapted to counteract the side-thrusts of both cutters between their inner ends and at a point below the center of their revolution.

18. In a pulverizer, a draft-frame and two vibrating cutters adapted to oppose each

other, in combination with mechanism located and acting between the inner ends of the cutters in the same vertical plane as the 70 cutters for limiting the vertical vibration of said cutters.

19. In a pulverizer, a draft-frame and two independently-revolving cutters, in combination with a wheel located between the inner 75 ends of said cutters and adapted to have contact therewith on opposite sides of said wheel.

20. In a pulverizer, two cutters and a draft-frame attached to the outer ends of said cutters, in combination with a center coupling 80 adapted to have contact at two points with the inner end of each cutter.

21. In a pulverizer, a draft-frame and two cutters, in combination with the buffer-rings *h h*, each ring being fastened to its cutter at 85 two points.

22. In a pulverizer, spiral cutters having continuous cutting-edges revolving independently of each other, and a draft-frame attached to the outer end of each cutter, in combination with a center coupling for the cutters, which permits the cutting-blades of one cutter to revolve in close proximity to the blades of its fellow cutter.

23. In a pulverizer, a spiral cutter, in combination with the buffer-ring *h* and web *w*.

24. As a new article of manufacture, a spiral cutter twisted from sheet metal, so as to form solid blades that are concave or dishing in cross-section, substantially as shown in 100 Fig. 10.

25. In a pulverizer, a draft-frame, in combination with two independently-revolving opposing spiral cutters, whose action can be reversed by applying the draft of the animals 105 in opposite directions relatively to said cutters.

26. In a pulverizer, a draft-frame, two vertically-vibrating cutters flexibly connected at their inner ends, and a seat adjustably hinged 110 to the draft-frame, in combination with mechanism for applying more or less of the weight of the driver directly to the inner ends of the cutters for limiting their vertical vibrations.

27. In a pulverizer, a draft-frame, two vertically-vibrating independently-rotating cutters arranged on opposite sides of the central-draft line, and a seat hinged to the draft-frame, in combination with adjustable mechanism attached to the seat by means of which 120 the pressure of the driver's weight upon the inner ends of the cutters can be varied.

28. In a pulverizer, a draft-frame adapted to be reversed by turning it upside down, two cutters, and a seat for the driver mounted on 125 the draft-frame, in combination with suitable seat-supporting devices which are adapted to maintain the seat upon opposite sides of the draft-frame.

29. In a pulverizer, a draft-frame with two 130 gangs of cutters connected therewith with their inner cutting-edges in close proximity to each other, the inner ends of the gangs having recesses extending into them beyond

the inner cutting-edges of the gangs, in combination with mechanism located within said recesses adapted to counteract or receive the side-thrusts of the gangs.

5 30. In a pulverizer, two gangs of cutters and a draft-frame attached to the outer ends thereof, in combination with independently-revolving wheel mechanism located between the inner ends of the gangs and adapted to

counteract the side-thrust of the same, the side-thrust of the gangs being imparted to or received by said wheel mechanism at a point thereon outside of its center of revolution.

CHARLES LA DOW.
